US0D1080533S

(12) **United States Design Patent** (10) **Patent No.:** **US D1,080,533 S**
(45) **Date of Patent:** **** Jun. 24, 2025**

(54) **WIRELESS CONTROLLER**

(71) Applicant: **Shenzhen IntelliRocks Tech. Co., Ltd.**,
Shenzhen (CN)

(72) Inventors: **Cheng Gong**, Shenzhen (CN);
Wenlong Wu, Shenzhen (CN)

(73) Assignee: **Shenzhen IntelliRocks Tech. Co., Ltd.**,
Shenzhen (CN)

(**) Term: **15 Years**

(21) Appl. No.: **29/853,216**

(22) Filed: **Sep. 14, 2022**

(30) **Foreign Application Priority Data**

Jul. 29, 2022 (CN) 202230491474.6

(57) **CLAIM**

The ornamental design for a wireless controller as shown and described.

DESCRIPTION

FIG. 1 is a front, right and bottom perspective view of a wireless controller, showing our design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

1 Claim, 8 Drawing Sheets
